PROPORTIONAL DIVIDER

Joseph F. Joy, Pittsburgh, Pa., assignor to Joy
Manufacturing Company, Pittsburgh, Pa., a
corporation of Pennsylvania

Application December 16, 1946, Serial No. 716,523

17 Claims. (Cl. 33—150)

1

This invention relates to drawing instruments and more particularly to an improved proportional divider having improved means for adjusting the pivotal point between the divider arms or leg members and for firmly holding the pivotal point in adjusted position, so that measurements taken from a drawing or the like may be increased or decreased according to scale as desired.

Proportional dividers of known makes usually have the divider arms or leg members thereof longitudinally slotted, and passing through the slots is a pivot pin or bolt having clamping means associated therewith to hold the slotted divider arms or leg members in their different positions of adjustment. Such known arrangements are not only relatively complicated and expensive to manufacture but are also subject to inadvertent slippage which hinders proper use of the instrument. The proportional divider of the present invention is provided with solid, non-slotted leg members, and the pivot and clamp is arranged externally of the non-slotted divider arms or leg members in a novel manner so that the pivot may be firmly held in its positions of adjustment. Further, by making the leg members solid and arranging the pivot and clamp externally thereof, it is found possible to decrease the cost of manufacture while, at the same time, making the instrument more reliable in use.

It is accordingly an object of the present invention to provide an improved drawing instrument which has many advantages over known devices. A further object is to provide an improved proportional divider having improved pivot means whereby the possibility of the selected adjustment of the divider arms or leg members becoming disturbed during use is substantially avoided. Yet another object is to provide an improved proportional divider having solid, non-slotted divider arms or leg members and improved clamping means arranged externally of the divider arms or leg members for firmly holding the pivot point thereof in adjusted position. A further object is to provide an improved proportional divider of a design which eliminates costly machining operations, enabling manufacture at less cost. A still further object is to provide an improved proportional divider which not only has decided advantages over known devices from the standpoint of manufacture and cost, but one which also may be used with greater accuracy and facility. Yet another object is the provision of an instrument of the above character which is extremely simple in construction, requiring but few component parts, thoroughly reliable and efficient in its purposes,

2

and inexpensive to manufacture, as well as strong and durable. These and other objects and advantages of the invention will, however, herein-after more fully appear.

5 In the accompanying drawing there are shown for purposes of illustration two forms which the invention may assume in practice.

In this drawing:

Fig. 1 is a front elevational view of a proportional divider constructed in accordance with a preferred illustrative embodiment of the invention.

Fig. 2 is a view in central longitudinal section taken substantially on line 2—2 of Fig. 1, with parts shown in full.

15 Fig. 3 is an elevational view similar to Fig. 1, with the divider arms in extended position.

Fig. 4 is a detail sectional view taken on line 4—4 of Fig. 3, illustrating details of the pivot and clamp.

20 Fig. 5 is a detail sectional view taken on line 5—5 of Fig. 4, showing the pivot structure.

Fig. 6 is a cross-sectional view taken centrally through the pivot on line 6—6 of Fig. 2.

25 Figs. 7 and 8 are, respectively, end and side views of the arm seat or bearing element.

Fig. 9 shows, in elevation, the combination spring and pivot disk which is used at the pivot point between the divider arms.

30 Fig. 10 is a cross-sectional view taken on line 10—10 of Fig. 9.

Fig. 11 is a cross-sectional view taken on line 11—11 of Fig. 2, showing the arm seat and slot structure.

35 Fig. 12 is a fragmentary view in central longitudinal section, illustrating a modified form of pivot and clamp.

Fig. 13 is a cross-sectional view taken on line 13—13 of Fig. 12.

40 Fig. 14 is a cross-sectional view taken on line 14—14 of Fig. 12, showing the arm slot structure.

In both illustrative embodiments of the invention, there is shown a proportional divider of novel construction having solid, non-slotted divider arms or leg members and an improved pivot and clamp structure arranged externally of the divider arms for firmly holding the adjustment of the pivot while freely allowing adjustment of the divider arms when desired. In the use of proportional dividers, it is oftentimes necessary to take a large number of measurements with the dividers set in one proportion, and in doing this, it often happens that the position of the pivot point becomes inadvertently shifted as a result of frequent handling of the instru-

ment, thus destroying the setting of the instrument and sometimes causing serious trouble in carrying out the work then in hand. By the use of the improved external pivot and clamp of the present invention, the probability of such disturbance of the adjustment is very slight. Also, by the provision of the improved pivot and clamp structure of the present invention, the pivot of the divider arms may be adjusted through a relatively wide range without the limitations of the longitudinal slots, previously referred to, in the divider arms of conventional dividers, and may be adjusted at any desired point between the extreme limits of the range of adjustment.

In the preferred illustrative construction shown in Figs. 1 to 11 inclusive, the proportional divider has but six component parts, and includes a pair of divider arms or leg members 1 and 2 which are of a solid, non-slotted construction and are held together by an external pivot or clamp structure, generally designated 3, of an improved design. The arms or legs are of a sturdy, though light, generally semi-circular cross section having plane inner adjacent surfaces 4 and curved outer surfaces 5. The outer arm surfaces are provided with numbered graduations stamped or otherwise imposed thereon comprising a scale 6, divided into suitable units, so that the divider may be readily set at the desired proportion. The arms or legs are provided at their long sides with points 1, 7 and at their shorter sides with points 8, 8.

The improved pivot or clamp structure 3 includes a generally cylindrical pivot-box or outer casing 9 having a uniform central bore 10, and the casing side walls are cut away or slotted at 11 to provide a seat 12 for the arm or leg 1 passing through the casing. Thus the arm 1 is held against pivotal movement with respect to the pivot-box 9 but is free to slide longitudinally in its seat 12 relative to the pivot-box. Adjoining the seat-slots 11 are segmental slots 13 extending circumferentially through the casing walls and through which the other leg or arm 2 passes, and the leg 2 is not only free to slide longitudinally with respect to the pivot-box but also to swing relative to the pivot-box within limits determined by the ends of the slots 13. Arranged in the casing-bore 10 and seated at 14 against a shoulder provided at the bottom of the bore is a circular seat element or pivot bearing 15 for the leg member 2, and the element 15 is slotted or grooved transversely at 16 at its inner side to conform to the contour of the curved outer surface 5 of the leg 2, as shown most clearly in Fig. 6. Thus a snug fit is provided for the pivoted leg 2. The seat or bearing element 15, when the clamp is loosened, is free to turn in the casing-bore, thereby to provide a swivel bearing for the pivoted leg 2 as the latter is swung in the arcuate slots in the casing walls. A combination spring and pivot disk 17, herein of dished form as shown in Fig. 10, affording some resiliency, is arranged within the casing-bore between the inner plane surfaces 4, 4 of the divider arms, and threaded at 18 within the outer threaded end of the casing-bore is a clamping nut 19 formed with a knurled grasping portion 20. When the nut is tightened, the divider arms are pressed toward one another, compressing the spring disk 17 to the desired tension between the legs and clamping the element 15 tightly against its seat 14, thereby firmly to hold the arm-pivot in adjusted position and to secure

the arms against longitudinal slippage. When the arms 1 and 2 are folded into closed position, as shown in Figs. 1 and 2, a pin 21 on the arm 2 enters a slot or notch 22 in the arm 1 to hold the arms against relative endwise sliding movement. Thus the arms may be readily folded and clamped together when not in use. The clamping nut 19 is centrally open at 23 to provide sight of the indicating numeral on the arm 1 at which the arm pivot is set, and the bearing element 15 has a central opening 24 and the end wall of the pivot-box 9 is centrally cut away to provide for similar observation of the corresponding indicating numeral on the arm 2.

15 The instrument is assembled, as shown in Figs. 2 and 6, and, upon assembly, the bearing element 15 is first placed in the bore 10 of the pivot-box against its seat 14. The arm 2 is next placed in the groove 16 through the segmental slots 13, and the combination spring and pivot disk 17 is next inserted in the casing bore 10 against the inner plane surface 4 of the arm 2. The arm 1 is then slid in place in the seat 12 and the clamping nut 19 may then be threaded into the casing-bore and tightened to hold the parts together. When in use, the divider may be set to the desired proportion by sliding both arms or legs 1 and 2 as a unit, when the arms are held together in closed position, relative to the pivot-box or 20 by sliding the pivot-box bodily relative to the arms, until the desired indicating numerals are centered within the observation openings 23 and 24. When the desired relation of the pivot arms has thus been made, the clamping nut 19 may 25 be screwed down, compressing the combination spring and pivot disk 17 to the desired tension between the divider arms. The instrument is thus made ready for use. In operation, the leg 1, by reason of its being snugly seated in the slot-seat 12 of the pivot-box, becomes firmly held to the box and moves therewith, whereas the leg 2 seated in the bearing seat of the element 15 which is rotatable relative to the pivot-box is free to move through the desired range of the 30 segmental slots 13 in the casing. Obviously, the tension between the divider arms may be adjusted to the desired degree by means of the clamping nut 19, thus regulating the pressure on the spring-disk 17 to the desired amount. By 35 locating the disk between the arms in the manner disclosed, the pivotal action of the arms is improved, thereby facilitating positioning of the arms. By reason of the arm 1 held against pivotal movement relative to the pivot-casing and the clamping nut 19, possibility of change of adjustment due to inadvertent slippage is substantially eliminated. Adjustment of the instrument from one ratio to another may be quickly accomplished simply by loosening the clamping nut and sliding the arms 1 and 2 in and out of the pivot-box or sliding the pivot-box bodily relative to the arms until the desired setting of the pivot is obtained.

40 In the modified embodiment shown in Figs. 12, 13 and 14, the divider arms, the pivot box, the clamping nut and the bearing element 15 for the arm 2 are generally like those of the embodiment above described. In this novel construction, the pivot box or casing 25 is segmentally slotted at 26 and 27 to receive both arms or legs 1 and 2 so that both arms may swing relative to the casing within limits determined by the ends of the slots. Arranged in the casing-bore is a pivot element 28 similar to the bearing 45 element 15 and similarly transversely slotted or

grooved at 29 at its inner side to conform to the curved outer contour of the arm 4. A clamping nut 30, similar to the clamping nut 19, engages the element 28 upon setting of the pivot. When the clamping nut is tightened, in the manner of the preferred embodiment, the combination spring and pivot disk 17 between the divider arms is compressed to the desired tension, and the elements are held firmly in position in the casing bore so that the proper setting of the pivot is made possible. By the provision of the rotatable bearing elements for each of the divider arms, it is possible not only to obtain firm setting of the pivot but also swinging and sliding adjustment of the arms is facilitated. If desired, the bottom end wall of the casing 25 may be formed with a threaded aperture to receive a suitable annular, open-centered screw plug so that the bearing element 15 may be inserted in place or removed through the bottom end wall of the casing without disturbing the clamping nut. Otherwise, this embodiment of the invention is similar to that above described.

As a result of this invention an improved drawing instrument is provided which has many advantages over previous devices, in that the setting of the pivotal point between the arms is facilitated and the possibility of inadvertent slippage of the pivotal point and longitudinal slippage of the arms is substantially reduced. The improved dividers are of a simple and sturdy construction, and due to their novel design, may be cheaply manufactured, since costly machining operations have been eliminated. By the provision of the improved pivotal mounting for the arms, eliminating excessive friction between the parts, adjustment of the arms is made relatively easy. These and other advantages and the manners of use of the improved drawing instrument will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a drawing instrument of the character described, a pair of relatively adjustable arms, an outer casing having a central bore and openings through the walls thereof through which said arms pass, one of said openings being in the form of a seat for one of said arms to hold the latter against swinging movement relative to said casing and the other opening being in the form of a segmental slot for permitting limited swinging movement of said other arm relative to said casing, and adjustable clamping means secured to said casing for moving one of said arms toward the other to clamp said arms in adjusted position relative to said casing.

2. In a proportional divider, a pair of relatively adjustable divider arms of solid cross section throughout their length and having pointed ends, and a pivot and clamp device including a pivot box arranged externally of said arms and having openings in its side walls through which said arms pass and one of said openings being laterally elongated to permit swinging movement of one of said arms relative to the other and to said pivot box, and adjustable clamping means

associated with said pivot box for moving said arms toward one another frictionally to hold said swingable arm against swinging movement relative to said other arm and said pivot box.

3. In a proportional divider, a pair of relatively adjustable divider arms having pointed ends, and a pivot and frictional clamp device including a clamp and pivot box arranged externally of said arms and having openings in its side walls through which said arms pass, a compressible spring and pivot element between said arms, and a single adjustable means secured to said box and adjustable relative thereto for moving one of said arms relative to the other to compress said spring and pivot element to hold both arms in adjusted position relative to said box.

4. In an instrument of the character described, a pair of relatively adjustable arms of solid cross section throughout their length, and a pivot and clamp device including a unitary casing member arranged externally of said arms and through which said arms extend, said device embodying a single adjustable clamping element adjustably secured to said casing member acting on one of said arms to move the arms toward one another to clamp both arms in adjusted position with respect to said casing member.

5. In a proportional divider, a pair of relatively adjustable divider arms having pointed ends, a cylindrical outer casing having circumferentially extending segmental slots in the walls thereof through which said arms pass to permit limited swinging movement of the arms relative to said casing, and an adjustable coaxial clamping element secured to said casing and adjustable relative thereto for moving one of said arms toward the other to clamp said arms in adjusted position relative to said casing.

6. In a proportional divider, a pair of relatively adjustable divider arms having pointed ends, an outer casing having a central portion and segmental slots in the walls thereof through which said arms pass to permit limited swinging movement of said arms relative to said casing, rotatable bearing elements in said casing bore and providing seats for said arms so that said bearing elements turn with said arms relative to said casing, and an adjustable clamping element secured to said casing and acting on one of said arms for moving the same toward said other arm to clamp said arms and said bearing elements in adjusted position relative to said casing.

7. In a drawing instrument of the character described, a pair of relatively adjustable arms of solid cross section throughout their length, and a pivot and clamp device including a pivot box arranged externally of said arms and having openings in the side walls thereof through which said arms pass, and a single adjustable element associated with said pivot box for moving said arms together frictionally to hold said arms in adjusted position in stationary relation with respect to said pivot box.

8. In a drawing instrument of the character described, a pair of relatively adjustable arms of solid cross section throughout their length, and a pivot and clamp device including a pivot box arranged externally of said arms and having openings in the side walls thereof through which said arms pass, rotatable bearing elements in said pivot box one for each arm, and a single clamping device associated with said pivot box for moving said arms together and holding said bearing elements against rotation thereby fric-

tionally to secure both arms in adjusted position relative to said pivot box.

9. In a drawing instrument of the character described, a pair of relatively adjustable arms, one of which has graduations on its outer side to provide a scale, and a pivot and clamp device providing a pivot for said arms and adjustably engaging said arms for effecting setting of the pivot clamp and including a rotatable adjustable element for securing said arms in adjusted position, said rotatable adjustable element having an axial opening therethrough to provide sight of one of said graduations when the same is positioned centrally of said opening.

10. In a drawing instrument of the character described, an arm having graduations along one side thereof, and an external arm clamp including a rotatable adjustable screw element formed with an axial sight opening so that one of said graduations which lies centrally of said opening may be readily observed.

11. In an instrument of the character described, a pair of divider arms, a pivot and clamp casing having openings through its side walls through which said arms pass, one of said openings being laterally elongated to permit relative swinging adjustment of said arms, and a single clamping element secured to said casing and adjustable frictionally to clamp said arms against axial movement and to resist swinging movement thereof relative to said casing.

12. In an instrument of the character described, a pair of relatively swingable and axially adjustable divider arms of solid cross section, a casing having a central bore, said casing having openings through the side walls thereof through which said arms pass and one of said openings being laterally elongated to permit relative swinging adjustment of said arms, arm-pivot means in said casing-bore, said pivot means turning in said bore with one of said arms during such relative swinging arm adjustment, and a single clamping screw threaded in said bore for frictionally clamping said arms against axial movement and to resist turning movement of said pivot means relative to said casing.

13. In a drawing instrument of the character described, a pair of relatively adjustable arms of solid cross section throughout their length, and pivot and clamping means arranged externally of said arms and including an outer casing unit having openings through its side walls through which said arms pass, one of said openings being laterally elongated to permit relative swinging adjustment of said arms with said arms in said elongated opening swingable relative to said casing unit.

14. In a drawing instrument of the character described, a pair of relatively adjustable arms of solid cross section throughout their length, and pivot and clamping means arranged externally of said arms and including an outer casing unit having openings through its side walls through which said arms pass, one of said openings being laterally elongated to permit relative swinging adjust-

ment of said arms with the arm in said elongated opening swingable relative to said casing unit, and a single clamping element adjustably secured to said casing for moving one of said arms towards the other to clamp both arms in adjusted position relative to said casing.

15. In a drawing instrument of the character described, a pair of relatively adjustable arms, an outer casing having a central bore and openings through the side walls thereof through which said arms pass, one of said openings being laterally elongated to permit relative swinging adjustment of said arms with the arm in said elongated opening swingable relative to said casing, a bearing element mounted in said bore to rotate relative to said casing and providing a seat for one of said arms, and a clamping nut threaded within the casing bore for moving one of said arms toward the other to clamp both arms and said bearing element in adjusted position relative to said casing.

16. In a drawing instrument of the character described, a pair of relatively adjustable arms, an outer casing having a central bore and openings through the side walls thereof through which said arms pass, one of said openings being laterally elongated to permit relative swinging adjustment of said arms with the arm in said elongated opening swingable relative to said casing, a combination spring and pivot disk arranged in said casing bore between said arms, and a clamping nut threaded in said bore for moving one of said arms toward the other to compress said spring-disk to the desired degree thereby to hold both arms in adjusted position relative to said casing.

17. In a drawing instrument of the character described, a pair of relatively adjustable arms, one of which has graduations along its outer side to provide a scale, and an adjustable pivot providing and clamping device arranged externally of said arms for providing a pivot for said arms and adjustable to prevent relative pivotal movement of said arms, said device including an element adjustable to provide a setting of the arm pivot and provided with a sight opening located centrally of said pivot providing and clamping device so that one of said graduations which lies centrally of said opening may be readily observed.
